HORATIO O. PERRY, OF BUFFALO, NEW YORK.

Letters. Patent No. 79,385, dated June 30, 1868; antedated June 16, 1868.

IMPROVEMENT IN FEED-WATER HEATERS FOR BOILERS.

The Schedule referred to in these Letters Patent and making part of the same.

TO ALL WHOM IT MAY CONCERN:

Be it known that I, HORATIO O. PERRY, of the city of Buffalo, in the county of Erie, and State of New York, have invented certain new and useful Improvements in Feed-Water Heaters for Steam-Boilers; and I do hereby declare that the following is a full and exact description thereof, reference being had to the accompanying drawings, in which—

Figure 1 is a side view of a portion of a boiler partially in section, showing the arrangement of my improved heater.

Figure 2 is a vertical section of the heater detached.

Like letters of reference designate corresponding parts in both figures.

The invention consists in the construction and arrangement of a feed-water heater within the smoke-box or chimney of a steam-boiler, substantially as hereafter described.

In the drawings, A represents the smoke-box, B the chimney or smoke-stack extending therefrom; C is the heater, arranged above the flues in the smoke-box and chimney.

The heater consists of a cylindrical or slightly-conical vessel placed upright, with a vertical flue or opening, D, passing through its centre. The shell or outer case e is made with its sides outwardly diverging towards the top, while the inner case or flue is made to converge, as shown in fig. 2, leaving between the two an annular water-space, F. Cold water is introduced into this space near the bottom, through a suitable pipe, g, which enters from the outside.

H is the feed-pipe near the top, through which the water, after it has become heated, is forced by the feed-pump into the boiler. I is a steam-pipe, which conveys the steam generated in the heater to the steam-dome.

The inclined or diverging and converging sides respectively of the case and flue of the heater cause more of the heated products of combustion to come in contact therewith, than would if they were vertical, with the draught ascending parallel along its sides. They also serve to slightly retard the passage of the heated products, which enables more of the heat to be absorbed.

The great advantages of my improved arrangement are obvious.

It utilizes the products of combustion after they have performed their office of generating steam in the boiler, and which would otherwise escape and be wasted.

In many arrangements the heater abstracts heat that would otherwise be employed in generating steam, by which there is lost in one direction what is gained in the other, whereas by my improved arrangement I am enabled to attain all the beneficial results of a heater, without any of the prejudicial consequences that usually attend its use.

The heater is also simple in its construction, and of a nature best calculated to accomplish the desired purpose. It can be easily applied to any ordinary boiler, and at but a trifling expense.

What I claim as my invention, is—

The heater C, constructed and arranged within the smoke-box and chimney, substantially as shown and described.

In witness whereof, I have hereunto signed my name in the presence of two subscribing witnesses.

HORATIO O. PERRY.
